UNITED STATES PATENT OFFICE.

WINSLOW R. PARSONS, OF CHICAGO, ILLINOIS.

WINDOW-SASH-OPERATING APPARATUS.

1,082,899.

Specification of Letters Patent. Patented Dec. 30, 1913.

Application filed December 19, 1910. Serial No. 598,026.

To all whom it may concern:

Be it known that I, WINSLOW R. PARSONS, a citizen of the United States, and a resident of Chicago, in the county of Cook and State of Illinois, have invented certain new and useful Improvements in Window-Sash-Operating Apparatus, of which the following is a specification.

This invention relates to improvements in window sash operating apparatus especially designed and intended for opening and closing very large and correspondingly heavy swinging sash, and may be shutters, heretofore essentially consisting of a pin projecting from and below the bottom edge of the sash into a continuously straight slot in a lever bent at its shank beyond the slot, and provided with a gear actuated by a worm supported from the window sill. With the pin thus located and the slot straight throughout its length the direction of the force applied during the initial opening and final closing of such a sash is tangential to the axis of the lever, and, therefore, substantially at a right angle to the length of the lever diametrically through the axis of the pin, and with the result that heretofore an objectionable amount of force has been necessary in the initial movement of the window from and to its closed position, which resistance is also increased to some extent by the location of the pin directly beneath the sash, but mainly because of the leverage being then the shortest.

The prime object of my invention, broadly stated, is an apparatus generally of this pin and slotted lever type in which the initial force exerted by the lever against the pin shall be on lines at a right angle to the axis of the lever and the pin located at a point removed from the sash, and the pin, as the result of all the forces moves on a line whereby the power for actuating the window immediately from and toward its closed position is reduced to a minimum.

A further object of my invention is to have the pin so located, with reference to the sash, that when the sash is closed the lever, its gear and the worm may be located inwardly beyond the sash, and thereby at a point where they are protected by the sash from outside moisture, and at the same time exposed to the influence of the internal dry and warm air of the room in which the window is located.

With these ends in view, my invention

finds embodiment in certain features of novelty in the construction, combination and arrangement of parts by which the said objects and certain other objects are herein-after attained, all as fully described with reference to the accompanying drawings, and more particularly pointed out in the claims.

In said drawings:

Figure 1 is a horizontal view in section through a window casing and sash having my invention applied thereto. Fig. 2 is a view in section on the line A—A of Fig. 1; and, Fig. 3 is a vertical section on the line B—B of Fig. 2.

My invention is concerned primarily with windows of the class which employ a casing *a* in which the sash *b* is pivoted at one side thereof by the hinges *c*. In a suitable recess in the casing I secure the operating mechanism which will be seen to consist of the shaft *d* having the worm *e* secured thereto, and for convenience in adapting the apparatus to sashes pivoted at the right or left hand as may be desired, I preferably secure the worm on the shaft by detachable connections, such as the screw *f*, so that the worm can be removed from the shaft and its direction reversed.

The worm shaft is journaled in the vertical sides *g* of the base plate *h*, which is secured to the bottom of the recess in any suitable manner as by the screws indicated. The base plate is preferably provided with a cover plate *i*, which is conveniently secured in place by the lugs *j* on the side pieces *g* passing through correspondingly shaped recesses in the top of the plate.

Journalized on a suitable bearing projecting upward from the base plate is the gear segment *k*, the teeth of which mesh with the worm *e*. This bearing may be conveniently formed by the pin *l* passing through the bearing disk *m* and apertures in the segment *k* and the cover plate *i*, the latter being held in place by the screw *n* and the washer *o*. The connection between the window sash and the gear segment is preferably formed by the arm *p* secured to the bottom of the window sash and carrying the projection *q* at its outer end, which projection preferably takes the form of an anti-friction roller and extends over the slot *s* formed in the arm *r* which is preferably formed integrally with the gear segment *k*.

In order to enable me to get the full

movement of the sash through 90 degrees and still get the arm in the narrow space allowed in the casing, I incline the inner end of the slot at t at the angle shown. The 5 shaft d is of course provided with a crank handle u , which may be detachably secured on the squared end of the shaft, if desired.

In the foregoing mechanism, it will be seen that I have devised a very simple and 10 powerful mechanism for opening a sash of the character described, which mechanism can be introduced into the narrow space allowable in the window casing, and it will further be seen that the mechanism herein 15 shown is arranged so as to give the greatest leverage at the start of the opening movement and at the end of the closing movement when the greatest power is required. It will also be noted that the co-action of 20 the worm and its gear serves to hold the sash in any position of adjustment.

While I have shown and described my invention as embodied in the form which I at 25 present consider best adapted to carry out its purposes, it will be understood that it is capable of modifications, and that I do not desire to be limited in the interpretation of the following claims except as may be necessitated by the state of the prior art. And 30 in this connection it should be observed that as to that feature of my invention providing for the application of a force from the lever to the pin on a line radial to the axis of the lever in the initial movement of the window from and toward its closed position, it will be no departure from my in-

vention to dispense with the arm p and have the pin project directly from the bottom of the sash.

What I claim as new, and desire to secure 40 by Letters Patent of the United States is:—

1. In a device of the class described, a window casing and a sash pivoted therein, a pin supported by the sash, a lever provided with an angular slot engaging said pin, a 45 worm and a gear connection between the lever and the worm, substantially as described.

2. In a device of the class described, a window casing and a sash pivoted therein 50 in combination with a worm, means for rotating it, a segment gear meshing therewith, a lever swung by said segment having a slot therein, the inner end of which slot is at an inclined angle, relative to its outer end 55 and a projection carried by the sash engaging said slot, substantially as described.

3. In a device of the class described the combination with a worm and means for rotating it, of a worm gear segment meshing 60 therewith, an arm swung by said segment having a slot therein with the inner end thereof acting as a cam, and a projection carried by the sash engaging the slot of the arm. 65

In witness whereof, I have hereunto set my hand and affixed my seal this 17th day of December A. D. 1910.

WINSLOW R. PARSONS. [L.S.]
